US00D829738S

(12) **United States Design Patent** (10) Patent No.: **US D829,738 S**
(45) Date of Patent: ** Oct. 2, 2018

(54) **DISPLAY SCREEN OR PORTION THEREOF
WITH GRAPHICAL USER INTERFACE**

(71) Applicant: **Illumina, Inc.**, San Diego, CA (US)

(72) Inventors: **Kai-How Farh**, San Mateo, CA (US);
Donavan Cheng, Foster City, CA (US);
Andrew Warren, San Diego, CA (US);
Ian D. Patrick, Lake Worth, FL (US)

(73) Assignee: **Illumina, Inc.**, San Diego, CA (US)

(**) Term: **15 Years**

(21) Appl. No.: **29/575,141**

(22) Filed: **Aug. 22, 2016**

(51) LOC (11) Cl. **14-04**

(52) U.S. Cl.

USPC **D14/486**

(57) **CLAIM**

The ornamental design for a display screen or portion thereof with graphical user interface, as shown and described.

DESCRIPTION

The FIGURE is an embodiment of the display screen with graphical user interface or a portion thereof with graphical user interface in accordance with the present invention. The broken line at the periphery of the FIGURE illustrate the display screen or portion thereof, and the remainder of the broken lines illustrate portions of the graphical user interface. None of the broken lines form part of the claimed design.

1 Claim, 1 Drawing Sheet
